UNITED STATES PATENT OFFICE.

WILLIAM T. SMITH, OF PHILADELPHIA, PENNSYLVANIA.

DESIGN FOR A RUG.

SPECIFICATION forming part of Design No. 19,605, dated January 21, 1890.

Application filed December 23, 1889. Serial No. 334,750. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design to be Woven in Chenille Rugs and Curtains, of which the following is a specification, reference being had to the accompanying photographic print, forming a part thereof, which conveys to any one skilled in the art of chenille-weaving a clear understanding of the same, and is sufficient to enable such person to use my invention.

The accompanying print shows but one half of the full design. The half not shown is exactly like the half that is shown.

What I claim as my invention, and desire to secure by Letters Patent, is—

The design for a chenille rug or curtain, consisting in the ornamentalations shown in the photographic print accompanying this specification.

W. T. SMITH.
